UNITED STATES PATENT OFFICE

LEON BENOIT AND E. JOSEPH KANABAY, OF CHICAGO, ILLINOIS; SAID KANABAY
ASSIGNOR TO SAID BENOIT

WRAPPING PACKAGES

Application filed February 18, 1930. Serial No. 429,407.

This invention relates to wrapping packages and particularly to the application to packages of wrappers which are adapted to be rendered air-tight, for example by sealing 5 the overlapping edges.

The invention particularly relates to the application of wrappings of waxed paper or other material which is adapted to become adherent when heat is applied thereto.

Although the invention is applicable to packages of various forms and sizes, it will be described in connection with packages of 10 eggs of a conventional type, as illustrated in the accompanying drawing, in which—

Figure 1 is a perspective view of a crate containing packages of eggs wrapped in accordance with the invention, parts of the crate and liner being broken away to show the wrapped packages in position,

Fig. 2 is a plan view of a machine adapted to assist in the application of the wrapping,

Fig. 3 is a perspective detail showing one stage of the application of the wrapper,

Fig. 4 is a similar view showing a later stage in the application of the wrapper,

Fig. 5 is a sectional view on the line 5 of Fig. 4.

Referring to Figs. 2 to 5 of the drawing, the wrapping machine comprises a table 20, to which is applied a metal plate 21, which is substantially the same shape and size as the base of the package which is to be wrapped.

Along its edges, side plates 22 and 23 and end 35 plates 24 are pivotally connected to the plate 21. The plates 22, 23 and 24 are adapted to lie upon the table outwardly from the plate 21 as shown in Fig. 2. The end plates 24 are spring

pressed by spring hinge members 10, or the like, so that they tend to move about their pivoted edges over the plate 21. Catches 25 mounted on the table 20 are adapted to engage the plates 24 and secure same against such movement until they are released during the 40 wrapping operation, as will be hereinafter described.

The side plate 22 may be somewhat shorter than the depth of the package to be wrapped. The side plate 23 is preferably substantially equal to that depth and has pivoted thereto along its outer edge a plate 26

which is suitably approximately half the width of the package.

Along its outer edge the plate 26 is provided with a heavy rib 27, which, as shown in Fig. 4, is adapted to be brought into contact with the central line of the top of the package during the wrapping operation. The end plates 24 are cut away at the center of their outer edges as shown at 28 to permit the package to be removed from the wrapping machine after the wrapping is completed.

The table 20 is bored as shown at 29 to receive a rod 30 which extends from one side of the table transversely of the plate 21 and preferably about its center. Suitable bearings 31 are provided for the rod 30 and a crank handle 32 is mounted on its outer end so that it may be rotated. Adjacent and beneath the plate 21 the bore 29 opens into a

transverse slot 32' and this slot gives into slots 33, in the longitudinal direction of the plate 21 for the reception of radial arms 34 which are mounted on the rod 30 adjacent the front and rear sides of the plate 21, that is, beneath the pivoted edges of the plates 22 and 23.

It will be readily understood that the arms 34 are located in the slots 33 when the plates 22 and 23 are in their horizontal position. When the crank 32 is rotated, the arms 34 raise the plates 22 and 23 into vertical position as shown in Figs. 3 to 5. Suitable stops 35 are mounted on the surface of the table 20 to serve as guides for the application of the wrapping paper or the like 36 upon the table as shown in Fig. 2.

The package to be wrapped may consist of a cellular carton produced by a blank A which is bent in the form of one or more troughs having certain transverse slots through which are inserted cross walls B, such a construction being shown and described in the Leon Benoit Patent No. 1,768,923 granted June 24, 1930. In wrapping such a package a sheet of waxed paper 36 is applied to the table over the plates 22, 23, 24 and 26 which are positioned flat upon the table, the plates 24 being engaged by the catches 25. The carton 37 is superimposed upon the plate 21 and reinforcing false ends 38 are applied to the recessed ends of the carton, in order to provide

smooth end surfaces therefor. False ends for this purpose may obviously be omitted in the case of other packages. The crank handle 32 is now rotated through an angle of about 90°, which results in the movement of the plates 22 and 23 into vertical position, which causes the sides of the sheet of paper 36 to be raised into vertical position above the top of the carton. The connection between the plates 23 and 26, is such that the plate 26 assumes an oblique position backwardly and upwardly from the top edge of the plate 23 as shown in Fig. 3 and indicated in dotted lines in Fig. 4. The operator now grasps the projecting sides of the sheet of paper, creases them together along a line parallel and adjacent to their lateral edges, and continues the folding operation so as to tighten the sheet around the package and enclose the folded edges close to the top of the package, as shown in Fig. 5. The plate 26 is now swung about its pivot so as to superimpose the rib 27 upon the folded joint so as to hold the wrapping in place while its application is being completed. The portions of the wrapper extending beyond the sides of the package are now folded inwardly over the ends of the package thus forming triangular flaps projecting from the top and bottom of the package at the ends thereof. The upper flaps are bent downwardly as shown in Fig. 4, and while still held in contact with the ends of the package, the catches 25 are released, whereupon the plates 24 spring into vertical position superimposing the lower flaps upon the upper flaps. The wrapping of the package is now completed and is ready for transfer to a sealing machine.

The packages of eggs which are thus wrapped and sealed may suitably be packed in crates, as shown in Fig. 1. It is preferred to employ a liner or envelope 96 which may suitably be of waxed paper. When the packages are packed within the said envelope, its free edges are folded together and preferably sealed by the local application of heat and pressure in succession. The eggs within the crate are thus protected by a double air tight inclosure which has valuable effects in preserving them from decomposition and deterioration of flavor.

Although the invention has been disclosed in connection with the details of specific embodiments thereof, it must be understood that such details are not intended to be limitative of the invention except insofar as set forth in the accompanying claims.

We claim:

1. A machine for wrapping packages comprising a table, plates pivotally mounted thereon and adapted to be positioned and releasably held flat on the table, and means normally urging said plates to move into vertical position.
2. A machine for wrapping packages com-

prising a table, plates pivotally mounted thereon and adapted to be positioned flat on the table, spring means normally tending to elevate said plates to a vertical position, and releasable means adapted to hold said plates adjacent the table.

3. A machine for wrapping packages comprising a table, four plates pivotally mounted thereon and adapted to be positioned flat on the table, the pivoted edges of said plates defining the position for the base of the package to be wrapped, means normally tending to elevate an opposed pair of plates to the vertical position, releasable means adapted to hold said plates adjacent the table, and manually operable means adapted to elevate the other pair of plates to vertical position.

4. A machine for wrapping packages comprising a table, opposed plates pivotally mounted thereon and adapted to be positioned flat on the table, means adapted to elevate said plates to apply a wrapper to the walls of packages, a plate pivotally mounted on one of said plates adapted to be moved over the top of said package, the last said plate having a weighted fold engaging portion to hold the folded joint of the wrapper against unfolding, opposed plates adapted to engage the remaining walls of the package, means adapted to releasably secure said plates positioned flat on the table, and means normally tending to elevate the last said plates into vertical position.

In testimony whereof, we have hereunto set our hands this 12th day of February, 1930.

LEON BENOIT.
E. JOSEPH KANABAY.
